CLAIM

The ornamental design for a fork lift truck, as shown.

DESCRIPTION

FIG. 1 is a perspective view taken from the left front of a first embodiment of a fork lift truck showing our new design;

FIG. 2 is a perspective view taken from the right rear of the fork lift truck of FIG. 1;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a perspective view taken from the left front of a second embodiment of the forklift truck showing our new design;

FIG. 10 is a top plan view thereof;

FIG. 11 is a bottom plan view thereof;

FIG. 12 is a front elevational view thereof;

FIG. 13 is a rear elevational view thereof;

FIG. 14 is a right side elevational view thereof; and,

FIG. 15 is a left side elevational view thereof.
